E. B. STRANGE.

PAIL.

APPLICATION FILED APR. 27, 1915.

1,296,132.

Patented Mar. 4, 1919.

Inventor,
E. B. Strange.

By his Atty. T. F. Bourne

UNITED STATES PATENT OFFICE.

EDWIN B. STRANGE, OF NEW YORK, N. Y.

PAIL.

1,296,132.

Specification of Letters Patent.

Patented Mar. 4, 1919.

Application filed April 27, 1915. Serial No. 24,180.

To all whom it may concern:

Be it known that I, EDWIN B. STRANGE, a citizen of the United States, and resident of New York city, borough of the Bronx, in 5 the county of Bronx and State of New York, have invented certain new and useful Improvements in Pails, of which the following is a specification.

One of the objects of my invention is to 10 provide a pail of integral fibrous pulp material which shall be cheap to manufacture, strong and durable and not liable to be crushed in transportation. A further object is to provide a cover for the pail made 15 of integral fibrous material, which shall be strong and durable and will aid in bracing the walls of the pail from inward crushing strains.

Among the further objects of my invention 20 is to provide a pulp structure having a plurality of sections and ribs so arranged relative to each other that the pressing and forming of the same will result in a more strongly braced and reinforced structure; 25 and further to provide a cover so arranged as to prevent crushing when the filled pails are stacked one upon the other, and means for securing the cover in position on the pail.

30 My invention further comprises novel details of improvement and combinations of parts that will be more fully hereinafter set forth and then pointed out in the claims.

Reference is to be had to the accompanying 35 drawings forming part hereof, wherein,

Figure 1 is a perspective view of a pail embodying my improvements;

Fig. 2 is a cross section on the line 2, 2, in Fig. 1;

40 Fig. 3 is an enlarged detail section on the line 3, 3, in Fig. 1;

Fig. 4 is a corresponding view at the opposite side of the pail; and

Fig. 5 is a detail hereinafter referred to.

45 The pail 1 has sides or walls 2 and a bottom 3 made integral, comprising fibrous pulp in suitable compressed form, which may be compressed to shape in any well known manner. At the inner corner 4,

50 where the sides and bottom join, the material is increased in thickness and made in a concave form in a continuous manner, integral with the sides and bottom, serving to increase the strength at the junction between the sides and bottom of the pail, to prevent the bottom and sides from becoming

cracked or broken during use, which is liable to occur where pails of this character are made with sharp or substantially right angled corners at the junction of the sides 60 with the bottom. This manner of constructing my improved pail may be carried out by suitably shaping the plunger at its outer edge, in rounded or convex form, so that the material of the pail when the same is pressed 65 or squeezed will provide a filling at the corner between the sides and bottom, thereby increasing the dimension of the material from such corner to the outer edge 5 of the pail. The bottom of the pail is shown recessed at 6 providing an annular rim 7, whereby the bottom of the pail may be made of the required thinness and yet strength is afforded at the margins by the rim 7 in conjunction with the filling 4.

70 The pail is formed of homogeneous pulp material by pressing wet pulp in such a way as to form integral sections and ribs that are so arranged relative to each other by the pressing and forming of the structure that 75 the pail is braced and reinforced throughout and greatly strengthened thereby.

75 By forming a pair of ribs 8 substantially parallel with each other and the adjacent ribs diverging therefrom from the bottom 80 upwardly as clearly shown in Fig. 1, the narrower sections 9 are substantially rectangular and the wider sections adjacent thereto on either side throughout the circumference of the structure gradually widen 85 from the bottom to the top of the pail, thereby providing a wedging and reinforcing action both during compression and after the pulp has hardened that increases the density of the pulp and supplements the 90 action of the ribs, some of which substantially parallel each other, while others diverge from the parallel ribs in such manner as to brace the homogeneous integral fibrous pulp pail in all directions and greatly 95 strengthen it and hence make it commercially practicable for carrying heavy substances of various kinds.

100 The sections 9 and 10, the ribs 8, the bottom 3, and the enlarged reinforcing corners 105 4 on the inner side of the pail are all pressed integrally by means of a suitable press from homogeneous fibrous material, and after the pail has been thus formed it is dried and allowed to set and harden, as a result of 110 which a light inexpensive and substantial pail is formed, which has no joints or seams

to afford leakage, joints or corners to house or collect foreign material, or regions of weakness to permit rupture of the pail.

- It has been found by actual test that when sufficient pressure is applied to the pail to create therein a stress beyond the breaking point that any rupture to the enlarged filling 4 and the lower corners of the pail will follow a line which conforms substantially to the letter S; thus showing that the strength of the pail at this point is unusually great and of such nature that no straight lines of cleavage can occur therein. The combination of the filling 4, the annular rim 7, and the substantially vertical parallel and diverging ribs on the outside of the pail is such as to afford unusually great strength in a compressed fibrous pail as is so important in commercial use.
- 20 The cover 11 is formed of an integral piece of material, such as the fiber or pulp before mentioned, compressed in suitable dies, forming an annular marginal portion 12 adapted to fit upon the rim of the pail, 25 and providing an inwardly projecting annular rib 13 on the cover adapted to fit within the rim of the pail, thereby enabling the central portion of the cover at 14 to be made relatively thin, but with the required 30 strength afforded near the marginal edges of the cover by the annular rib 13. When the cover is in position upon the pail, as shown in Fig. 2, the annular rib 13 serves to brace the sides or walls of the pail against inward pressure.
- 35 On the sides of the pail I provide plates 15, which may be secured to said sides by means of staples, rivets or the like 16. Said plates 15 are provided with projections 17 pressed out from the plate and having apertures 17^a to receive the bent ends of bail 19, whereby the bail is pivotally connected with the pail. Plates 15 are also provided with loops 18 which are struck out from the metal 40 of the plates and located above projections 17. At 20 is a sealing strip or band for the cover, of suitable material, such as metal strips adapted to be folded into coaction with the loops 18. One end of strip 20 is shown folded through a loop 18 in such 45 manner that the main part of the strip passes over an end portion thereof that overlies the loop, as shown in the enlarged view of Fig. 4, a portion of the strip thus lying between loop 18 and plate 15, another portion of the strip overlying said loop, and a further portion of the strip overlying the last named end portion thereof, whereby the latter is securely attached to the loop and 50 prevented from pulling loose. From said loop 18 strip 20 is passed upwardly over the top of the pail and over the cover, thence across the cover and down the other side of the pail, where it is passed through the corresponding loop 18 and is thence reversed

and carried upwardly, and its two parts are secured together, as by crimping them by a suitable tool, as shown at 21. The strip 20 may thus be drawn tight in connection with the loops 18 to securely retain the cover in place on the pail, and as said loops 18 are on plates 15 above the pivotal points of the bails with the projections 17 of said plates, the bail is free to swing upwardly to enable carrying the pail as well as freely passing the strip or band 20 without interfering with the latter.

Having now described my invention what I claim is:—

1. A pressed fibrous pulp structure having substantially vertical reinforcing ribs pressed integral with the sides thereof, some of which are substantially parallel and others diverging.

2. A compressed fibrous pulp pail, or analogous structure, comprising a body portion having substantially rectangular sections and substantially trapezoidal sections formed by pressing ribs between the sections to reinforce and strengthen the structure.

3. A pressed fibrous pulp structure having substantially vertical reinforcing ribs pressed integral with the sides thereof, some of which are substantially parallel and others diverging, and having an enlarged reinforcing juncture pressed between the sides and bottom thereof.

4. A pressed fibrous pulp structure having substantially vertical reinforcing ribs pressed integral with the sides thereof, some of which are substantially parallel and others diverging, and a cover therefor having an annular reinforcing rib pressed integral therewith adjacent to the edge thereof.

5. A pressed fibrous pulp structure having substantially vertical reinforcing ribs pressed integral with the sides thereof, some of which are substantially parallel and others diverging and having an enlarged reinforcing juncture pressed between the sides and bottom thereof, and a cover therefor having an annular reinforcing rib pressed integral therewith adjacent to the edge thereof.

6. In a pressed fibrous pulp pail, a body portion having longitudinal ribs pressed integral therewith, some of said ribs being parallel and others of said ribs being inclined relative to said parallel ribs, a cover on said pail having a marginal seat resting on the rim of said pail and an annular depending flange adjacent said seat and fitting within said rim whereby said pails when filled may be stacked on each other without crushing.

7. A pressed fibrous pulp structure having substantially vertical reinforcing ribs pressed integral with the sides thereof, some of which are substantially parallel and oth-

ers diverging and having an enlarged reinforcing juncture pressed between the sides and bottom thereof, a cover therefor having an annular reinforcing rib pressed integral therewith adjacent to the edge thereof, and means for securing said cover to said structure.

Signed at New York city, in the county of New York, and State of New York, this 26th day of April, A. D. 1915.

EDWIN B. STRANGE.
